UNITED STATES PATENT OFFICE.

DANIEL A. OSGOOD, OF JERSEY CITY, NEW JERSEY.

GROUTING-MACHINE.

1,024,224.

Specification of Letters Patent.

Patented Apr. 23, 1912.

Application filed January 3, 1911. Serial No. 600,478.

Be it known that I, DANIEL A. Osgood, a citizen of the United States, and a resident of Jersey City, county of Hudson, and State of New Jersey, have invented certain new and useful Improvements in Grouting-Machines, of which the following is a full, clear, and exact specification.

This invention relates to a class of machines adapted to force under pressure cement or other water-proofing substances in powder or semi-liquefied form for preventing leakage of water through the walls of tunnels, pipe lines, etc.

My invention has for its object primarily to provide a device or grouting machine of simple construction by the use of which fissures, crevices, broken away parts, and the joints of the walls of submarine or other tunnels and pipe lines may be quickly and efficiently filled with cement or like suitable material either in dry powder or semi-liquid form for repairing or water-proofing said walls; and to provide a form of machine adapted to throw the material under high atmospheric pressure.

Another object of the invention is to provide a form of tank or receptacle in which is carried a supply of the filling or repairing material; and to provide in conjunction therewith valve controlled means adapted to regulate the atmospheric pressure supplied to said tank for forcing therefrom the required quantity of the material.

Still another object of the invention is to provide a tank or casing having interiorly thereof a form of means adapted to mix the filling material received therein from the supply tank and assist in forcing the material to a distributing pipe connected thereto; and to provide in conjunction with said receiving tank valve controlled means adapted to permit sufficient compressed air to be supplied for clearing the receiving tank of all material when desired.

A further object of my invention is to provide a valve controlled outlet or feed pipe for proper distribution of the filling material; and to provide in conjunction therewith valve controlled means adapted to permit the filling material when fed to the outlet pipe in dry form to be mixed with a required quantity of water, or other liquid, or steam, so as to use said material in a semi-liquefied form.

With these and other objects in view, the

invention will be hereinafter more particularly described with reference to the accompanying drawing, which forms a part of this specification, and will then be pointed out in the appended claims.

The drawing is a side elevation of one form of grouting machine embodying my invention.

In practice my grouting machine 10 may be supported by any suitable means so that the supply tank or receptacle 11 will preferably be in a vertical position. In one part of the top of the supply tank 11 is an inlet pipe 12 through which is passed the cement or water-proofing material either in a dry or semi-liquefied form, and in one part of the bottom of said tank is provided an outlet pipe or nozzle, as 13, having a valve 14 of any preferred form which is adapted to permit the passage therethrough of the contents of the supply tank 11 when it is desired to clear said tank of all material, for instance, when the machine 10 is not in use. The tank 11 is interposed between one end of a discharge pipe 15 and one end of an air inlet pipe 16. Interposed in the inlet pipe 16 is a valve 17 of any well known make by which the compressed air pressure through said pipe may be conveniently regulated, and in the discharge pipe 15 is interposed a suitable valve 18 adapted to control the volume of cement or other material to be forced therethrough. At the opposite end of the inlet pipe 16 is held a transversely disposed main air supply pipe 19 to which is connected a pipe 20 leading to the source of compressed air supply for operating my machine. To one end of the main supply pipe 19 is joined one end of a vertical air feed pipe 21 and adjacent to the opposite end thereof is interposed a valve 22 of any preferred make adapted to regulate the air pressure through said feed pipe. Connected to the opposite end of the main supply pipe 19 is one end of a second vertical air feed pipe 23, and in proximity to the opposite end thereof is interposed a valve 24 of suitable form to also control the air pressure through said pipe.

A receiving tank or casing, as 25, is supported at the end of the discharge pipe 15 opposite to the supply tank 11 and has one part thereof also connected to the opposed end of the feed pipe 21. The receiving tank 25 is preferably circular in form and is disposed transversely with respect to the

supply tank 11. One end of the receiving tank 25 is closed by a head-plate 27 and in the opposite end of said body is a second plate 28. For the purpose of relieving the receiving tank 25 of all surplus material therein an outlet pipe 29 having its passage controlled by a suitable valve 30 is provided at the opposed part of the body 26 to which is connected the feed pipe 21 and is also arranged upon said body opposite to the discharge pipe 15.

To one edge of the plate 28 of the receiving tank 25 is joined one end of a distributing pipe 31 which also joined to the feed pipe 23, and in said distributing pipe between the tank and its union with the pipe 23 is interposed a valve 32 of any usual form adapted to regulate the flow there-through of the filling material discharged from the tank 25. Upon the opposite end of the distributing pipe 31 is a pipe 33 to which any desired form of nozzle may be attached for properly directing the discharged material to the parts of a tunnel or place where it is to be used. Interposed in the distributing pipe 31 between the feed pipe 23 and nozzle pipe 33 is an observation tube 34 which may be of glass or other transparent material whereby the character of the mixed material and quantity of discharge thereof may be carefully watched.

In case it is desired to discharge from the supply tank 11 and from the receiving tank 25 the material in dry powder form and provide for converting the material to a semi-liquid consistency by the use of water or other liquid before its final discharge through the pipe 33, a supply pipe 35 having a suitable cut-off valve, as 36, is connected to the distributing pipe 31 between the feed pipe 23 and observation tube 34, or when desired to mix the dry material with the water or other liquid after it has passed through the observation tube 34 a second supply pipe 37 in which is interposed a cut-off valve 38 is connected direct to the pipe 33.

To thoroughly mix the cement or material whether in the dry form or if semi-liquefied when forced from the supply tank 11 into the receiving tank 25, and to also assist in feeding the material to the distributing pipe 31 I provide within said receiving tank a form of means, as 39. The means 39 consists of a rotatable shaft or rod 40 having one end journaled in the plate 28 and the opposite part thereof is journaled in the head plate 27. At intervals upon the shaft 40 is rigidly held a plurality of mixing devices 41, each of which is formed of two oppositely disposed blades 42 and 43 which are obliquely arranged with relation to each other, and as the material is fed into the receiving tank 25 the devices 41 are revolved by manually operating a crank handle 44 provided upon the end of the shaft 40 extending from the head plate 27 exteriorly of the receiving tank 25.

In operating my grouting machine a sufficient quantity of the cement or other material is passed through the inlet pipe 12 into the receiving tank 11 and the valve 17 of the inlet pipe 16 and valve 18 of the discharge pipe 15, as well as the valve 32 of the distributing pipe 31 are thrown open. 75 The compressed air from the source of supply will be directed through the pipe 20, through the main supply pipe 19, and into the supply tank 11 through the inlet pipe 16. The material will then be discharged 80 from the tank 11, through the pipe 15 and into the receiving tank 25. The valve 22 is then thrown open for passage of the compressed air through the feed pipe 21 into the tank 22 and against the material therein 85 which is being simultaneously mixed and forced toward the distributing pipe 31 by the blades 42 and 43 of the mixing means 39 during rotation of the crank handle 44. As the material is passing through the distributing pipe 31 the valve 24 is opened and a second charge of compressed air is directed against the material through the feed pipe 23, and in this manner the material will be delivered from the pipe 33 with sufficient 95 force to readily fill all crevices, fissures or like openings for rendering tunnels and pipe lines proof against leakage. 90

In the foregoing description I have embodied the preferred form of my invention, 100 but I do not wish to be understood as limiting myself thereto, as I am aware that modifications may be made therein without departing from the principle or sacrificing any 105 of the advantages of this invention, therefore I reserve to myself the right to make such changes as fairly fall within the scope thereof.

Having thus described my invention, I claim as new and desire to secure by Letters Patent:

1. In a grouting machine; in combination; a supply tank having an inlet pipe in the top thereof and through which may be passed material; a discharge pipe having one end connected to the opposite end of the supply tank and having a cut-off valve interposed therein; a tank connected to the opposite end of the discharge pipe and disposed transversely with respect to the supply tank; a distributing pipe having one end connected to one end of the receiving tank; an air inlet pipe having one end connected to the end of the supply tank opposite to said discharge pipe 115 and having a valve interposed therein; a main supply pipe held to the opposite end of said air inlet pipe and adapted to transmit air under pressure to the air inlet pipe 125 from a source of air supply; and means pro- 130

vided within the receiving tank and adapted to mix material when forced therein from the supply tank through said discharge pipe.

5. 2. In a grouting machine; in combination; a supply tank having an inlet pipe in one part of the top thereof for the passage therethrough of material and having in one part of the bottom a valve controlled discharge nozzle; a discharge pipe having one end connected also to the bottom of the supply tank and having a cut-off valve interposed therein; a receiving tank connected to the opposite end of the discharge pipe and disposed transversely with respect to the supply tank; a distributing pipe having one end connected to one end of the receiving tank; an air inlet pipe having one end connected to the top of the supply tank and having a valve interposed therein; a main supply pipe held to the opposite end of said air inlet pipe and adapted to transmit air under pressure from a source of air supply to the supply tank through the air inlet pipe; means adapted to transmit air under pressure from the main supply pipe to the end of the receiving tank opposite to the distributing pipe; and means provided within the receiving tank and adapted to mix material when forced therein from the supply tank through said discharge pipe.
3. In a grouting machine; in combination; a supply tank having an inlet pipe in one part of the top thereof for the passage therethrough of material and having a valve controlled discharge nozzle in one part of the bottom of said supply tank; a discharge pipe having one end connected also to the bottom of the supply tank and having a cut-off valve interposed therein; a receiving tank connected to the opposite end of the discharge pipe and disposed transversely with respect to the supply tank; a distributing pipe having one end connected to one end of the receiving tank; a main supply pipe held to the opposite end of said air inlet pipe and adapted to transmit air under pressure from a source of air supply to the supply tank through the air inlet pipe; means adapted to transmit air under pressure from the main supply pipe to the end of the receiving tank opposite to the distributing pipe; and means provided within the receiving tank and adapted to mix material when forced therein from the supply tank through said discharge pipe.
4. In a grouting machine; in combination; a supply tank having an inlet in one

part of the top thereof for passage of material and having in one part of its bottom a valve controlled nozzle; a discharge pipe having one end connected also to the bottom of the supply tank and having a cut-off valve interposed therein; a receiving tank connected to the opposite end of the discharge pipe and disposed transversely with respect to the supply tank; a distributing pipe having one end connected to one end of the receiving tank; a main supply pipe adapted to transmit air under pressure from a source of air supply; means adapted to transmit the compressed air from the main supply pipe to the supply tank; means adapted to transmit air under pressure from one end of the supply pipe to the end of the receiving tank opposite to the distributing pipe; means provided within the receiving tank and adapted to mix material when forced therein from the supply tank through said discharge pipe; and means adapted to transmit the compressed air from the opposite end of the main supply pipe to the distributing pipe.

5. In a grouting machine; in combination; a supply tank having an inlet pipe in one part of the top thereof for passage of material and having in one part of its bottom a valve controlled nozzle; a discharge pipe having one end connected also to the bottom of the supply tank and having a cut-off valve interposed therein; a receiving tank connected to the opposite end of the discharge pipe and disposed transversely with respect to the supply tank; a distributing pipe having one end connected to one end of the receiving tank; a main supply pipe adapted to transmit air under pressure from a source of air supply; valve controlled means adapted to transmit the compressed air from the main supply pipe to the supply tank; an air feed pipe having one end connected to one end of the main supply pipe and its other end connected to the end of the receiving tank opposite to the distributing pipe and having an air pressure regulating valve interposed therein; a second feed pipe having one end connected to the opposite end of the main supply pipe and its other end connected to the distributing pipe; and means provided within the receiving tank and adapted to mix material when forced therein from the supply tank through said discharge pipe.

6. In a grouting machine; in combination; a supply tank having an inlet pipe in one part of the top thereof for the passage of material therethrough and having in one part of its bottom a valve controlled nozzle; a discharge pipe having one end connected also to the bottom of the supply tank and having a cut-off valve interposed therein; a receiving tank connected to the opposite end of the discharge pipe; and means adapted to transmit air under pressure from the opposite end of the main supply pipe to the distributing pipe.

- ing pipe having one end connected to one end of the receiving tank; an air inlet pipe having one end connected to the top of the supply tank and having an air pressure regulating valve interposed therein; a main supply pipe connected to the opposite end of the air inlet pipe and adapted to transmit air under pressure from a source of air supply to the supply tank 5 through said inlet pipe; a feed pipe having one end connected to one end of the main supply pipe and having its opposite end connected to the end of the receiving tank at the end thereof opposite to the distributing pipe, said feed pipe also having an air pressure regulating valve interposed therein; and means provided within the receiving tank and adapted to mix material when forced therein from the supply tank 10 through said discharge pipe.
7. In a grouting machine; in combination; a supply tank having an inlet pipe in one part of the top thereof for the passage of material therethrough and having in one part of its bottom a valve controlled nozzle; a discharge pipe having one end connected also to the bottom of the supply tank and having a cut-off valve interposed therein; a receiving tank connected to the opposite end of the discharge pipe; and having a valve controlled outlet pipe provided in one part thereof opposite to said discharge pipe; a distributing pipe having one end connected to one part of the receiving tank and having a cut-off valve interposed therein adjacent to said receiving tank; an air inlet pipe having one end connected to the top of the supply tank and having an air pressure regulating valve interposed therein; an air feed pipe having one end connected to one part of the receiving tank opposite to the distributing pipe and having an air pressure regulating valve interposed therein; a second air-feed pipe having one end connected to the distributing pipe and having an air pressure regulating valve interposed therein; a main supply pipe connected to the opposite ends of the first air feed pipe, the air inlet pipe, and the second air feed pipe and adapted to transmit air under pressure from a source of air supply to the air inlet pipe and to the first and second feed pipes whereby the compressed air may be transmitted at intervals to the supply tank, to the receiving tank and to the distributing pipe; and means provided within the receiving tank and adapted to mix material when forced therein from the supply tank through said discharge pipe.
8. In a grouting machine; in combination; a supply tank having an inlet in one part of the top thereof for the passage of material therethrough and having in one part of its bottom a valve controlled nozzle; a discharge pipe having one end connected to the bottom of the supply tank and having a cut-off valve interposed therein; a receiving tank connected to the opposite end of the discharge pipe and disposed transversely with respect to the supply tank; and a distributing pipe having one end connected to one end of the receiving tank and having a cut-off valve interposed therein adjacent to said receiving tank; means provided within the receiving tank and adapted to mix material when forced therein from the supply tank through said discharge pipe; an air inlet pipe having one end connected to the top of the supply tank and having an air pressure regulating valve interposed therein; an air feed pipe connected to the opposite end of the air inlet pipe and to the top of the receiving tank; and a main supply pipe connected to the opposite end of the air inlet pipe and to the end of the air feed pipe.

jet pipe and adapted to transmit air under pressure from a source of air supply to the supply tank through said air inlet pipe; valve controlled means adapted to transmit compressed air from one end of the main supply pipe to one end of the receiving tank opposite to the distributing pipe; valve controlled means adapted to transmit compressed air from the opposite end of the main supply pipe to the distributing pipe adjacent to the cut-off valve thereof; an observation tube interposed in the distributing pipe; valve controlled means provided in the

distributing pipe adjacent to the observation tube and adapted to supply water to said distributing pipe; a discharge pipe connected to the end of the distributing pipe; and a valve controlled means connected to the discharge pipe and adapted to supply water to said discharge pipe.

This specification signed and witnessed this thirty first day of December A. D. 1880.
